UNITED STATES PATENT OFFICE.

HOLLIS A. MCTAGUE, OF EAST HOLDEN, MAINE.

PRIMER FOR INTERNAL-COMBUSTION ENGINES.

Application filed December 24, 1925. Serial No. 77,521.

My invention relates to improvements in primers for internal combustion engines, the primary object being to provide means actuatable from the dash-board of an automobile or the like vehicle, for closing the usual air inlet of the fuel feed device, to permit feeding of raw gas or the like charge to the engine.

A further object is to provide a foot-operated device of this character which is mounted upon the dash-board of an automobile and in which the foot pedal is readily adjustable to differ angles for the purpose of adapting the device to machines of different types. It is likewise an object to construct a device of this character which may be readily attached to the usual dash-board with comparatively slight alterations in the dash-board construction and readily attached to the operating crank of the usual butterfly valve without any alteration whatever.

With the foregoing and minor objects in view, the invention resides in the novel subject matter hereinafter described and claimed, the description being supplemented by the accompanying drawing.

Figure 1 is a side elevation illustrating the application of my invention;

Figure 2 is a side elevation showing my device in idle position;

Figure 3 is a similar view showing the parts positioned to close the usual butterfly valve;

Figure 4 is a fragmentary front elevation of an automobile dashboard showing my invention mounted thereon; and

Figure 5 is a sectional view taken substantially on line 5—5 of Fig. 2.

It is understood that this construction is readily adaptable to fuel inlets of feed devices of different types, though for the purpose of this application I have shown it associated with a carburetor of the usual form employed in connection with the Ford type of internal combustion engine, this carburetor including the usual air inlet 1 which has a butterfly control valve 2 provided with a lever 3 which may be readily operated from the radiator, not shown, by means of an operating rod 4 which extends forwardly from the carburetor. My invention is adapted to be mounted upon the dashboard 5 of an automobile at a point adjacent the foot-board 6, and broadly consists of a bell crank, one end of which is so formed as to serve

as a foot pedal, while the other end is connected to the aforementioned butterfly operating lever 3. A spring device is arranged in connection with this bell crank lever so as to normally retain the butterfly valve 2 in open position.

In mounting this apparatus upon a dash-board 5, the latter is provided with a vertical slot 7 about whose inner end is arranged a face plate 8 carrying transversely aligned bearing members or ears 9 for the reception of a transversely arranged pin or stub shaft 10 as shown in Fig. 5. This plate is fixed to the dashboard 5 by means of bolts or any other suitable fasteners 11. It will be noted in Fig. 2, that the ears or bearing members 9 are arranged adjacent the lower end of the slot 7 so that when the bell crank is in its normal position, the lower end wall 12 of the slot will serve as a stop and limit the downward movement of the forward end of said bell crank.

The bell crank consists of a relatively short arm 13 provided near its rear end with a transverse opening in which is received the aforementioned stub shaft or cross pin 10, the outer end of this arm 13 being turned downwardly and apertured for a purpose to be pointed out. The opposite end of this bell crank is provided with a disk-like head upon one side of which is formed a set of radial-teeth or serrations 14 which extend radially from a transverse opening 15 aligned with a similarly formed opening 16 in a disk head 17 carried at one end of a foot pedal or lever 18 as shown in Figs. 2 and 5. A screw bolt or the like 19 connects the pedal 18 and the arm 13 and has a knurled finger-piece 20 by means of which said elements may be readily separated either entirely or a sufficient amount to permit relative angular adjustment. It will be noted in Fig. 4 that the head 17 of the foot pedal 18 is also provided with serrations or radial teeth 17' which coact with the aforementioned teeth to positively lock the pedal 18 and the arm 13 at any preferred angle. It is understood that it will be quite advantageous to embody this adjustable feature in this apparatus, since through this adjustment, the apparatus may be readily adapted to different types of machines in which the dash-boards and footboards are relatively differently positioned. Further, since the dashboard 5 serves as a stop for limiting the inward movement of the pedal 18, it

naturally follows that the degree of this movement controls the extent to which the butterfly valve 2 is actuated and consequently, the operator may predetermine the extent of movement of the butterfly valve by changing the relative angles of the lever or foot pedal 18 and the arm 13.

Fixed to the downwardly turned end 21 of the arm 13 is a link comprising a pair of 10 transversely spaced arms or bars 22 which are pivoted between their ends to the outer portions of a transverse pin 21' carried by the downturned portion 21. The lower end of this link device is connected to the upper 15 end of the connecting rod 23 whose lower end is pivoted to the butterfly valve operating lever 3 as shown in Fig. 1.

While other types of spring devices may be employed to retain the parts in the positions shown in Fig. 2, I preferably pivotally connect a head 24 to the upper end of the aforementioned link, this head carrying a guide rod or stem 25 about which is arranged a coil expansion spring 26 whose upper end 25 bears against the horizontal flange 27 of a bracket 28 which is secured to the forward face of the dashboard 5. This horizontal flange portion 27 of the bracket 28 is provided with an apertured boss 29 which serves 30 as a bearing for the guide rod or stem 25 and prevents undue lateral movement of this rod.

The normal position of this apparatus is shown in Fig. 2, the forward end of the arm 13 being in contact with the stop portion 12 so as to normally retain the butterfly valve 2 in open position as shown in dotted lines in Fig. 1. In starting an internal combustion engine, the foot pedal 18 is pressed forwardly into engagement with the dashboard 5 with the result that the butterfly valve 2 is moved to close the air inlet opening. With this positioning of the valve, a rich charge of gasoline is drawn into the internal combustion engine during the priming period, after which the foot pedal may be released to permit the coil spring 26 to act for the purpose for opening the valve 2 for obvious purposes.

It is understood that certain changes in the minor details of construction may be resorted to and such of these changes as may fall within the scope of the appended claims, I consider within the spirit of my invention.

I claim:

1. In an apparatus of the character described, the combination with a fuel feed device having a valved air inlet and an operating lever therefor, of a support having a

transverse opening, an arm extending 60 through and pivoted in the lower end of said opening, the lower wall of the opening forming a stop for one end of said arm, an actuating member fixed to the other end of said arm, a link device pivoted to one end of the 65 arm, connection between one end of the link device and said operating lever, a bracket having a guideway, a rod having one end, slidably arranged in the guideway, and its other end connected to the link device, and a 70 coil expansion spring on the rod to normally inter-engage the stop and said arm to open the inlet.

2. A structure as specified in claim 1; said actuating member being pivotally fixed to 75 the arm, inter-engaging teeth on contacting faces of said arm and member, and means for locking the arm and actuating member at different relative angles.

3. In a primer of the character described, 80 the combination with a dashboard having a vertical slot and bearings associated with said slot; an arm journaled intermediate its ends in said bearings and extending through and beyond opposite entrances to the slot, a 85 stop arranged below one end of the arm and formed by the lower end wall of said slot, means directly engaging one end of the arm and normally yieldably holding the stop and arm inter-engaged, and a foot pedal depending from the other end of said arm.

4. In an apparatus of the character described, the combination with a fuel feed device having a valved air inlet and an operating lever therefor, of a support having a 90 transverse opening, an arm extending through and pivoted in the lower end of said opening, the lower wall of the opening forming a stop for one end of said arm, an actuating member fixed to the other end of said 95 arm, a connection between the first mentioned end of the arm and said operating lever, a bracket having a guide-way, a rod having one end slidably arranged in the guide-way and its other end connected to 100 the last named end of said arm, and a coil expansion spring surrounding a portion of the rod to normally effect yieldable interengagement of the stop and arm.

5. A structure as specified in claim 4; 110 pivotal connection between said actuating member and the arm, and inter-engaging teeth carried by the arm and actuating member to permit positive locking of said members at different relative angles. 115

In testimony whereof I have hereunto affixed my signature.

HOLLIS A. McTAGUE.
